John Murphy, Jr.
Attorney

UNITED STATES PATENT OFFICE.

HERBERT C. HARRIS, OF SPOKANE, WASHINGTON.

HIGHWAY CONSTRUCTION.

1,375,960.

Specification of Letters Patent. Patented Apr. 26, 1921.

Application filed April 15, 1919. Serial No. 290,266.

To all whom it may concern:

Be it known that I, HERBERT C. HARRIS, a citizen of the United States, residing at Spokane, in the county of Spokane and State of Washington, have invented certain new and useful Improvements in Highway Constructions; and I do hereby declare the following to be a full, clear, and exact description of the invention, such as will enable others skilled in the art to which it appertains to make and use the same.

My invention relates to improvements in roads and more particularly to roads constructed of a plurality of sections.

An important object of this invention is to provide a road constructed of a plurality of sections having their abutting edges extending diagonally across the road whereby a vehicle upon traveling on the road will engage but one of its wheels at a time with the joints of the sections.

A further object of the invention is to provide novel means for interlocking the sections of the road whereby the same are prevented from lateral displacement.

A further object of the invention is to provide a road which is durable, of highly simplified construction and desirable in use.

Other objects and advantages of the invention will be apparent during the course of the following description.

In the accompanying drawing forming a part of this application and in which like numerals are employed to designate like parts throughout the same,

The figures are plan views of portions of a road illustrating different modifications of my invention.

In the drawing wherein for the purpose of illustration is shown some preferred embodiments of my invention, the numeral 5 generally designates a road constructed of a plurality of sections 6. The sections may be of such material as asphalt, concrete, or other hard material which expand and contract under the influence of hot and cold weather respectively. The sections 6 have their abutting edges 7 extending diagonally of the road whereby a vehicle upon crossing each meeting place of the sections will engage but one of its wheels at a time with the meeting places of the sections and the ve-

hicle will thereby pass smoothly over the meeting places.

In the form of my invention illustrated 55 in Figure 1 one longitudinal edge portion of each of the sections 6 is provided with a rectangular recess or pocket 8, receiving longitudinally extending tongues 9 carried by the adjacent edges 7. 60

The interfitting connection between the sections 6 prevents lateral displacement of any of the sections and retains them in longitudinal alinement.

In the form of my invention illustrated 65 in Fig. 2, the sections 10 are provided with diagonally disposed abutting edges 11. One vertical edge portion of each of the sections 10 is provided with a V-shaped recess 11 receiving V-shaped tongues 12 carried by the 70 adjacent edges of the sections 10. The interfitting connection between the several sections 10 prevents displacement of the sections.

In the form of my invention illustrated 75 in Fig. 3, the sections 13 are provided with diagonally disposed abutting edges 14. The longitudinal edge portions of the sections extend transversely of the road and thereby prevent lateral displacement of the 80 sections.

In the form of my invention illustrated 85 in Fig. 4, the sections 15 are provided with diagonal abutting edges 16 extending entirely across the road.

Having thus described my invention, what I claim is:—

A paving section in the form of a parallelogram having edge side and end edges at two of its diagonal corners intersecting 90 each other at acuminate angles and its edges at the other two diagonal corners intersecting each other at obtuse angle, the section being provided at the obtuse angle portion with notches and provided at 95 its acuminate corners with tongues, the tongues and notches being located at parallel edge portions of the section.

In testimony whereof I affix my signature in presence of two witnesses.

HERBERT C. HARRIS.

Witnesses:

HENRY PETERS,
G. T. BROWN.
